SOUND RECEIVING DEVICE

Richard M. Somers and Henry S. Carlson, West Orange, N. J., assignors to Thomas A. Edison, Incorporated, West Orange, N. J., a corporation of New Jersey

Application September 16, 1938, Serial No. 230,194

5 Claims. (Cl. 177—311)

This invention relates to sound-receiving devices and the like, and more particularly to sound-receiving devices which are provided with auxiliary indicating and/or controlling means.

5 While the invention is not in all aspects limited thereto, it has particular utility and is described in connection with phonographs.

In phonographs—particularly phonographs of the dictating machine type—there are commonly 10 employed sound receiving devices provided with phonograph-controlling means, these devices being arranged to be grasped by the operator as he speaks thereto. On or within such sound-receiving devices there may be aptly located a signal 15 light for indicating to the operator the condition of the phonograph.

The objects of this invention are to mount the signal light on the sound-receiving device in such a manner as to render the light readily visible 20 while enhancing the appearance of the receiving device, to render the receiving device safe so that the operator may grasp it with freedom from electrical shock, and yet to provide a mounting for the light permitting the light to be readily 25 removed from the receiving device.

Other objects are to provide a movable mounting for the signal light which is of simple construction, and which is readily adaptable to a phonograph sound-receiving device differing 30 from conventional forms to only such extent as involves relatively small increase in manufacturing cost.

Still other objects will appear from the following description and the appended claims.

35 In the description of my invention reference is had to the accompanying drawing, of which:

Figure 1 is a cross sectional view, taken substantially centrally therethrough, of a sound-conveying device in which my invention is incorporated, some interior parts thereof being shown in elevation;

Fig. 2 is a cross sectional view taken substantially along the line 2—2 of Fig. 1;

45 Fig. 3 is a fragmentary cross-sectional view taken substantially along the line 3—3 of Fig. 1; and

Fig. 4 is a reduced cross sectional view taken substantially along the line 4—4 of Fig. 1.

50 Reference being had to Fig. 1, there will be seen a sound conveying device of a form adapted for use with phonographs of the dictating machine type. This sound-conveying device comprises a handpiece 1 having a sound conduit 2 which is slightly curved and gradually flared out-

wardly. The inner and smaller end of the sound conduit 2 is provided with a reinforced extension 3 arranged to make connection with one end 4 of a speaking tube 4, and be retained thereto as by a set screw 5. The other end of the speaking tube 4 may make connection with a phonograph or the like, this other end portion of the tube 4, as well as the phonograph, being unnecessary to show. Threaded into the outer and larger end of the conduit 2 is a mouthpiece 6 preferably having an inner perforated wall 7 serving as a barrier against the passage of dirt into the conduit 2, yet not impeding the passing of sound waves therethrough. The handpiece 1 is arranged to be grasped by the operator and held, during the operation of recording, in a position wherein the mouthpiece 6 is directly before his mouth so that the sound waves from his mouth may be collected by the mouthpiece and conveyed by the conduit 2 and speaking tube 4. It will also be understood that during an operation of reproducing the operator may hold the sound-conveying device to his ear, the mouthpiece 6 then serving as an earpiece. To permit such freedom of movement of the sound-conveying device, the speaking tube 4 is made quite flexible.

At the rearward portion of the handpiece 1—the place where the operator normally grasps the handpiece—there may be provided a phonograph-controlling device 8. This control device may comprise a single-pole double-throw switch having pole member 9 and contact members 10 and 11 carried in a stack 11, such form of switch being commonly employed for controlling phonograph clutch-actuating mechanisms, for example mechanisms of the type described in Langley Patent No. 1,380,486 and issued June 7, 1921. This control device may be housed in a compartment 12 having the front and back walls 13 and the side walls 14 shown in Fig. 4, each of these walls being preferably integrally formed with the handpiece 1. The top of compartment 12 may be enclosed by a cover 15 pivoted at its rearward end 15' to the side walls 14, as by a pin 16. The cover 15 is biased upwardly by a spring 17, into a position as shown in Fig. 1, this position being defined by a screw 18 threaded in the forward wall 13 and extending into an elongated slot 19 provided in a downwardly extending flange 20 50 at the forward portion 15'' of the cover 15. The cover 15 is provided with side flanges 21 shown in Fig. 4, which slidably contact the side walls 14 to guide the cover 15 inwardly thereof, these side flanges 21 together with the flange 20 also serv-

ing to maintain the compartment 12 substantially closed when the cover 15 is in its upward position. Electrical connection may be made to the control device 8, as by a cable 22 running from the compartment 12 through an eyelet 22' into the speaking tube 4.

When the cover 15 is in its upward position the pole member 9 is biased, as by a spring 23, into contact with the contact member 10, the spring 23 also serving as a conductor for the pole member 9. As the cover 15 is moved downwardly, as by the grasp of the operator's hand, an inwardly projecting element 24 of the cover 15 abuts against the pole member 9 so as to move it downwardly into contact with the other contact member 11, thereby throwing the switch.

Whenever a signal light is located on a sound-conveying device of the type hereinabove described, it is highly desirable that the light be located so that it is readily visible, yet not abruptly projecting from the handpiece; it is moreover highly important that the light be suitably protectively covered to prevent any possible electrical shock to the operator and to prevent possible breakage of the light, yet being conveniently removable from the handpiece as for replacement thereof. It is moreover obviously important that the handpiece and signal-light mounting be low in manufacturing cost. In our invention we provide an arrangement of signal light and sound-conveying device fulfilling all of the desirable objectives hereinabove noted.

The handpiece 1, which is preferably a molded integral piece of insulating material, is provided with a recess 25 in the wall of the conduit 2. This recess is located forwardly of the compartment 15 and is preferably of a form having an outer wall portion 25' of substantially semicircular cross section as shown in Fig. 3, this portion being arranged to form a substantially smooth forward extension of the side walls 14 of the compartment 15. The forward wall portion 26 of the recess 25 is made gradually sloping to enhance the appearance of the handpiece 1, and in the portion 26 there is provided an opening or window 27. The recess 25 provides a convenient location for a signal light 28. Although the walls 25' and 26 of the recess do not project abruptly from the handpiece 1 but rather project out gradually along lines lending beauty to the handpiece, the opening 27 renders the signal light 28 yet readily visible to the operator as he holds the handpiece before him to speak thereinto. The inner surface 25'' of the walls 25' forming the recess 25 may be highly polished in order that the signal light 28 may be visible through a wide angle by the reflected light from the surface 25''. In the above arrangement, it will be seen that with the use of a suitable screw driver the screw 18 may be readily adjusted by way of the opening 27.

The supporting means for the signal light 28 comprises a flat rectangular plate 29 which is made of a conductive and resilient material. The plate 29 is disposed within and along the conduit 2 and is supported, in cantilever fashion, by the screws 30 which pass through the wall of the conduit 2 and thread into a small plate 31 secured, as by solder, to the plate 29. In order that the plate 29 may also serve as a conductor for the light 28, the plate 29 is electrically connected with a conductor in the form of a thin plate 32, disposed at the bottom of the compartment 12, by means of the heads 30' of the screws 30 which pass through the plate and make elec-

trical contact therewith. Resting on the plate 32, and retained in electrical contact therewith as by a screw 33', is a conductor in the form of relatively thick bar 33 which forms an electrical connection between the conductor or biasing spring 23 for the pole member 9 and the plate 32. Thus the plate 29 is electrically connected with the pole member 9. (The bar 33 also serves as a support for a bracket 34, secured thereto as by welding, which carries a cross pin 34' serving as a pivot for the pole member 9.) The plate 29 extends forwardly between the recess 25 and the passageway of the conduit 2. The forward end portion 29' of the plate 29 supports, and makes electrical connection with the shell 15 35' of a light socket 35 for the signal light 28, by way of a right angle bracket 36 secured to the light socket and retained to the plate 29 by the rivets 37 shown in Fig. 2. A second electrical connection to the socket 35 and light 28 is effected by a conductor 38 which passes through the conduit 2 and the speaking tube 4.

To the forward end portion 29' of the plate 29 there is connected a plate extension 39 which forms with the portion 29' a partition between the recess 25 and the passageway of the conduit 2. The plate extension 39 is curved to conform to the curvature of the conduit 2, and is insulated from the plate 29 by an insulating plate 40 which is secured to the plate extension 39 by the rivets 41 and to the plate 29 by the aforementioned rivets 37 and another rivet 42. The plate extension 39 is normally urged upwardly, as seen in Fig. 1, against the wall of the conduit 2, this upward urging of the plate extension 39 being effected by an upward biasing of the resilient plate 29. While the plate extension 39 is maintained in such upward position, its side edges 39'' conform closely to the wall of the conduit 2. At the front of the recess 25 there is provided a flat shoulder 43 which the plate extension 39 contacts throughout its width while the plate extension 39 is in its upward position. Thus the plate extension 39, together with the portion 29' of the plate 29, divides the recess 25 from the passageway of the conduit 2, and forms a compartment for the signal light 28. As a result the sound waves are effectively prevented from entering the recess 25 and the signal light is sufficiently shielded from the passageway of the conduit 2 to prevent it from being seen by way of the mouthpiece 6.

The forward end portion 39' of the plate extension 39 is extended sufficiently forwardly to abut against a shoulder 6' provided on the mouthpiece 6, when the mouthpiece is threaded into the conduit 2. By such abutment the plate 29 and plate extension 39 are firmly held in their normal position. When the mouthpiece 6 is removed, the portion 39' is readily accessible and serves as a fingerpiece which may be grasped and moved downwardly against the spring force of the plate 29 into a position such as is shown in dash-dot lines in Fig. 1. It is for the purpose of preventing possible electrical shock to the operator as he grasps the portion 39' that the plate extension 39 is insulated from the plate 29. When the plates 39 and 29 are in their downward position, the signal light 28 is readily accessible for removal from the socket 35. Upon release, the plate 29 will snap back to restore the signal light 28 in its normal position within the recess 25.

Although we have herein described and illustrated a particular embodiment of our invention,

it will be understood that the same is subject to many changes and modifications without departing from the scope of our invention, which we undertake to express according to the following

5 claims:

We claim:

1. In a device of the character described: the combination of an open-ended sound conduit provided with an interior recess within the conduit, a signal positioned in said recess and out of the passageway of the conduit, a movably mounted holder in said conduit for said signal operable to move the signal from said recess into the passageway of the conduit whereby to render 15 the signal accessible from the open end of the conduit, and resilient means biasing said holder to normally retain the signal within said recess.

2. In a device of the character described: the combination of an open-ended sound conduit 20 having a wall portion providing an interior recess in said conduit and a window in said recess, a signal light positioned in said recess and out of the passageway of the conduit and rendered visible to the outside by way of said window, and 25 support means in said conduit for said signal light comprising a movably mounted holder biased to normally retain the signal light within said recess and manually movable into a constrained position to move the light from said recess into 30 said passageway whereby to render the light accessible for replacement from the open end of the conduit.

3. In a device of the character described: the combination of an open-ended sound conduit having 35 a wall portion providing an interior lateral recess within the conduit and a window in said recess; a signal light adapted to be positioned

within said recess; and support means in said conduit for said signal light, comprising a holder for the light movable transversely of the passageway of the conduit to move the light out of said recess into said passageway whereby to render 5 the signal light accessible from the open end of the conduit, and spring means biasing said holder to normally retain the light in said recess.

4. In a device of the character described: the combination of an open-ended sound conduit 10 having a wall portion providing an interior recess in said conduit and a window in said recess; a signal light; a movably mounted support in said conduit for said signal light having a position wherein said signal light is held within 15 said recess at said window and having another position wherein the signal light is held out of said recess in the passageway of the conduit and is rendered accessible from the open end of the conduit; and means associated with said support 20 for forming, when the support is in the first of its said positions, a partition between said recess and said passageway.

5. In a device of the character described: the combination of an open-ended sound conduit; a 25 mouthpiece removably secured to the open end of said conduit; a signal in said conduit having a normal position of operation removed from the open end of the conduit; a mounting in said conduit for said signal movable to place the signal 30 into a position within the open end portion of the conduit; and means, engaged by said mouthpiece when the same is secured to said conduit, for holding said mounting to retain said signal in its said normal position of operation. 35
